UNITED STATES PATENT OFFICE.

NATHAN R. MAYOZA, OF MEMPHIS, TENNESSEE.

DESIGN FOR AN AUTOMOBILE SIGNAL.

Application filed March 14, 1925. Serial No. 12,722. Term of patent 14 years.

To all whom it may concern:

Be it known that I, NATHAN R. MAYOZA, a citizen of the United States, residing at Memphis, in the county of Shelby and State of Tennessee, have invented a new, original, and ornamental Design for an Automobile Signal, of which the following is a specification, reference being had to the accompanying drawing, forming a part thereof.

Fig. 1 is a rear view of the automobile signal embodying my design.

Fig. 2 is a side view of the same.

I claim,

The ornamental design for an automobile signal as shown.

In testimony whereof I have hereunto set my name.

NATHAN R. MAYOZA.
